CLAIM

The ornamental design for an inhaler device, as shown and described.

DESCRIPTION

FIG. 1 is a perspective view of a first side of an inhaler device showing the new design;

FIG. 2 is a side elevational view of the first side of the inhaler device of FIG. 1;

FIG. 3 is a side elevational view of a second side the inhaler device of FIG. 1;

FIG. 4 is a front view of the inhaler device of FIG. 1. The broken lines in the drawing of FIG. 4 illustrate portions of the article and form no part of the claimed design;

FIG. 5 is a back view of the inhaler device of FIG. 1;

FIG. 6 is a top view of the inhaler device of FIG. 1;

FIG. 7 is a bottom view of the inhaler device of FIG. 1; and, FIG. 8 is a back perspective view of the inhaler device of FIG. 1; the broken lines of the drawing of FIG. 8 are for illustrative purposes only and form no part of the claimed design.

The broken lines shown in the drawings illustrate portions of the article and form no part of the claimed design.

1 Claim, 7 Drawing Sheets
